(57) **CLAIM**

The ornamental design for an eyewear brow bar, as shown and described.

DESCRIPTION

FIG. 1 is a top, front, right side perspective view of an eyewear brow bar;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged detail view of a portion of FIG. 1;

FIG. 9 is an enlarged detail view of a portion of FIG. 2;

FIG. 10 is an enlarged detail view of a portion of FIG. 3;

FIG. 11 is an enlarged detail view of a portion of FIG. 4;

FIG. 12 is an enlarged detail view of a portion of FIG. 5;

FIG. 13 is an enlarged detail view of a portion of FIG. 6; and,

FIG. 14 is an enlarged detail view of a portion of FIG. 7.

The broken lines shown depict environmental subject matter only and form no part of the claimed design. The dash-dot-dash broken lines shown in the drawings define various boundaries of the claimed design and form no part of the claimed design.
